SAFETY ALARM FOR GAS BURNERS

William Mehlman, Eggertsville, N. Y.

Application April 24, 1930, Serial No. 446,842

1 Claim. (Cl. 200—137)

This invention relates to safety alarms for gas burners.

One of the objects of this invention is the provision of improved means associated with a gas burner or burners to cause a signal, either audible or visible, to be given in the event the gas pressure fails and extinguishes all burners.

Another object of my invention is to provide, in association with a pilot light and the main burner or burners of a stove, heater, and the like, means to automatically light the main burner or burners in the event that the latter are accidentally blown out and to prevent the escape of gas from the main burner or burners in the event that a child turns off the gas and playfully turns the gas on again, or in the event the gas is accidentally turned on after having been turned off.

A still further object is to provide a normally open thermostatically-controlled circuit closer in association with the pilot light; said circuit closer being of novel construction and serving to establish an electric circuit in the event of the pilot light becoming extinguished.

With the above and other objects in view to appear hereinafter, my invention consists in the novel features of construction, and in the arrangement and combination of parts to be hereinafter described, and more particularly pointed out in the subjoined claims.

In the drawings:

Fig. 1 is a plan view of a four-burner stove; part of the top being broken away to illustrate the main burners, the location and association of the pilot-burner thereto, and other parts of my invention in one of the forms now considered desirable.

Fig. 2 is an enlarged vertical section through the pilot-burner and associated parts, taken on line 2—2, Fig. 1.

Fig. 3 is a horizontal section taken on line 3—3, Fig. 2.

Fig. 4 is an enlarged vertical section taken on line 4—4, Fig. 1, looking toward the left.

Fig. 5 is a plan view of the control valve, part of the regulating valve and a portion of the gas supply pipe leading to the pilot-burner.

Fig. 6 is a horizontal section taken on line 6—6, Fig. 4.

Fig. 7 is an enlarged section taken on line 7—7, Fig. 1.

Fig. 8 is a modification of my invention.

In the particular application of my invention shown in the drawings, the numeral 10 designates a kitchen stove having the usual top, shown partly broken away, but invariably provided with

openings directly over the burners adapted to be closed with lids or griddles. The main burners, designated 11 are therefore exposed, as well as various parts adjacent thereto to better illustrate this invention. Each of said burners has an individual gas-pipe 12 connected therewith, so that they may be lighted at will. The usual air-mixer 13 is connected to each pipe and gas-cocks 14 connected to the gas supply pipe 15 project into the air-mixers in the usual way.

Arranged equi-distantly between the main burners 11 is a pilot burner 16 which is enclosed in a casing 17. This casing has a top wall 18, a surrounding or peripheral wall 19 and a bottom 20 through which a gas pipe 21 extends from the gas supply pipe 15, the pilot-burner 16 being threaded onto the inwardly-extending portion of pipe 21, which is immovably secured in said bottom by nuts 22, 23 applied thereto at opposite sides of the bottom. The pilot-burner may be of any construction and is designed to consume the gas issuing therefrom in the form of a steady comparatively small flame.

The bottom of the casing 17 is provided with air openings 24 and the surrounding or peripheral wall 19 also has air openings 25. The necessary air to maintain the pilot flame may, however, be furnished in any other approved manner.

The main burners 11 have safety lighter-pipes or conduits 26 formed integrally therewith, or connected thereto as shown in Fig. 8. Said safety lighter-pipes are perforated at intervals along their length, as at 27, and extend into the air openings 25 in pilot-burner casing 17, their outer ends terminating in close proximity to the pilot-burner. The purpose of these safety lighter-pipes is to conduct gas from the main burners to the flame of the pilot-burner, and they may therefore be disconnected from the main burners and arranged in any manner which will insure the passage of the gas from the main burners to the pilot-burner and the conveying of a flame from the pilot-burner back to the gas escaping directly from the burners. While I consider any means suitable to accomplish such action as falling fully within the scope of the appended claims, I have found the gas and flame-conveying means shown and described very effectual.

Pipe 21 supplying gas to the pilot-burner has a regulating valve 28 therein provided with a tapering port 29, opened to any desired degree by a needle valve 30 threaded through the casting of the valve and having its pointed end entering said port to provide for the passage of the desired quantity of gas therethrough, de-

pending on the size of the pilot flame required, and at times on the gas pressure.

In pipe 21 there is also arranged a shut-off control valve 31. This valve is shown between the regulating valve 28 and the gas supply pipe 15, but may be located between the regulating valve and the pilot burner, if desired.

Carried by and insulated from the surrounding or peripheral wall 19, or as it may be termed, 10 the side wall of the pilot burner casing, is a binding post 32 which carries a fixed electrical contact 33. A second binding post 34 is carried by and insulated from said side wall 19 and has electrical connection with a movable contact 35. In the form shown, said movable contact is carried by a vertically-disposed arm 36 15 pivotally and electrically secured at a point between its ends to the inner end of the binding post 34 and having its lower end enlarged to serve as a weight tending to swing the upper end thereof, and more particularly the contact 35 at the upper end thereof, in contact with the fixed contact 33, except when prevented by the heat of the pilot flame, which is utilized for 20 such purpose. The parts just described form a circuit closer. Separation of the contacts 33 and 35 is accomplished by means of a thermostatic device which, in the form shown is a slender rod or member 37 located over the pilot- 25 burner and horizontally disposed so that the pilot flame plays thereagainst, or at least so that the heat from the pilot flame will be effective thereon.

This thermostatic rod or member, of course, 30 possesses the qualities of expanding under heat and contracting when cooled, and it is adjustably arranged in the side wall 19 of the pilot-burner casing and insulated therefrom. For this purpose the outer portion of said rod or member 35 is enlarged and screw threaded, as at 38, into an insulating bushing 39 secured in said side wall in any suitable manner, and it has a knurled head 40 at its outer end for conveniently adjusting the rod to bring the inner end thereof 40 in proper relation to the movable or pivotal contact arm 36, so as to allow the contact 35 of said arm to engage the fixed contact 33 when the thermostatic rod or member is contracted or cooled, and to cause said movable contact to 45 move away from the fixed contact when the thermostatic rod is expanded by the pilot flame or the heat therefrom.

This thermostatic rod is normally in engagement with or may be spaced from the pivoted contact arm 36 beneath the pivot thereof, and in either case, the rod is contracted sufficiently to allow the pivoted arm 36 to assume a position which will bring the contact 35 thereof in engagement with the fixed contact. When, 50 therefore the pilot-burner is lighted, the heat therefrom will cause the thermostatic rod to expand and swing the lower weighted end of the contact outwardly, while the upper or contact end swings inwardly away from the fixed contact 33; thus breaking an electrical circuit which includes a bell 41 or some other suitable signal or alarm, a battery 42 or other source of current, and suitable current conductors of any kind leading to the binding posts 32 and 34. 55 In the drawings, I have shown wires 43, 44, 45 and 46 and the gas pipes 15 and 21 utilized for such purpose.

The shut-off valve 31 in the gas pipe 21 leading to the pilot-burner, comprises a casing 47 75 and a rotatable valve plug 48 therein through

which a passage 49 is formed capable of passing all the gas required at the pilot-burner, even though said plug is not rotated to its full extent, and said valve plug has a stem 50 projecting from its upper end and a laterally extending electrical contact 51 from its periphery which is adapted, under certain conditions, to contact with a segmental electric contact 52 adjacent the valve casing and secured to an insulation support 53 surrounding the inlet branch 54 of the valve 10 casing. Said segmental contact has one of the circuit wires 46 connecting it with the binding post 34, and is therefore included in the electrical circuit in which the signal or alarm is arranged. The contacts 51 and 52 serve as a 15 circuit breaker.

I have illustrated and described the valve plug of the shut-off valve 31 as provided with a stem, or it may have any other means whereby a separate or detachable handle or key will be employed for rotating the valve plug; thus guarding against children shutting off the supply of gas to the pilot burner and guarding against accidental closing of the shut-off valve.

Normally, the electrical circuit is broken by 25 separation of the contacts 51 and 52 associated with the shut-off valve 31; and, therefore, when first lighting the pilot light, the valve plug in said shut-off valve is only partially rotated so that the contact 51 projecting from said valve 30 plug will not come into engagement with the segmental contact 52. The necessary supply of gas will, however, pass through the passage 49 in said valve plug and be delivered to the pilot burner to be ignited. Consequently, no signal or 35 alarm will be given during such actuation of the shut-off valve. However, when the flame or heat from the flame of the pilot burner has expanded the thermostatic rod 37, it will have swung the pivoted arm 36 to cause separation of the contacts 33 and 35, after which the valve plug may be fully opened so as to engage the contact 51 with the contact 52, or in other words, close the circuit breaker. No alarm, however, will be given, due to the fact that the electrical circuit 40 is now broken at the thermostatically controlled circuit closer, and this condition is maintained so long as the gas escaping from the pilot burner is ignited. The size of the flame at the burner is conveniently regulated by adjusting the needle 45 valve 30 of the regulating valve 28.

If any one or more of the main burners 11 are to be ignited, it is only necessary to open the gas cocks 14 in the supply pipes thereof, whereupon the gas will issue from said burners and also 55 travel through the lighter pipes or conduits 26, with the result that this gas becomes ignited at the pilot light, and as the gas issues from the perforations in said lighter pipes or conduits, the flame is carried to the main burners 11 to ignite 60 the gas escaping therefrom. It will therefore be understood that, so long as the pilot burner is lighted, the opening of the gas cocks controlling the main burners, whether accidental or intentional, will prevent the escape of gas from said 65 burners, as the safety lighter pipes or conduits 26 will instantly serve to light the escaping gas at said burners.

In the event that the pressure of the gas is reduced to a degree that the pilot light becomes 70 extinguished, or if for any other reason gas is not supplied to the pilot burner, the thermostatic rod will cool and allow the pivoted arm 38 to swing on its pivot and establish an electric circuit, with the result that the signal or alarm is given. 75

The control valve 41 is then shut off until a proper flow of gas is again assured.

It will be apparent from the foregoing, that my invention guards against asphyxiation, and 5 also explosions in the event of the escaping gas being accidentally ignited.

Having thus described my invention, what I claim is:

In a device of the kind described, the combination with a casing, of a horizontally-disposed thermostatic rod adjustably secured within the peripheral wall of said casing and extending thereinto, two circuit-connected binding posts secured to said peripheral wall in vertical alignment opposite the point of securing said thermostatic rod to said wall, and a vertically-disposed contact element within said casing arranged for

movement on a horizontal pivot whose axis is disposed at a right angle to the axis of said thermostatic rod, said contact element being in electrical connection with one of said binding posts and mounted on said pivot between its ends 5 and having its lower end weighted and its upper end adapted for contact with the other of said binding posts, said weighted end causing said element to swing on said pivot in one direction into contact with said last-mentioned binding post 10 when said thermostatic rod is contracted and said contact element being in engagement at a point beneath its pivot with said thermostatic rod and being caused to swing in an opposite direction away from said last-mentioned binding 15 post when said thermostatic rod is expanded.

WILLIAM MOHLMAN.
